(57) **CLAIM**

The ornamental design for a wiring storage furniture, as shown and described.

DESCRIPTION

FIG. 1 is a perspective view of a wiring storage furniture.

FIG. 2 is a front elevation view thereof.

FIG. 3 is a rear elevation view thereof.

FIG. 4 is a right side elevation view thereof. A left side elevation view is a mirror image of the right side elevation view.

FIG. 5 is a top plan view thereof.

FIG. 6 is a bottom plan view thereof.

FIG. 7 is an enlarged cross-sectional view taken along the line 7-7 in FIG. 2; and,

FIG. 8 is a cross-sectional view taken along the line 8-8 in FIG. 2.

The broken lines shown in the drawings illustrate portions of the wiring storage furniture that form no part of the claimed design.
